WARP BEAM LETOFF FOR LOOMS

Thomas M. Russell, Jr., Middletown, Conn., assignor to The Russell Manufacturing Company, Middletown, Conn., a corporation of Connecticut

Application August 26, 1947, Serial No. 770,707

5 Claims. (Cl. 139—109)

1

The present invention relates in general to looms and more especially to improved let-off mechanism for the warp-beam of a loom.

Heretofore it has been customary for loom operators or weavers to be in constant attendance on the loom in order to check the tension of the warp strands during the life of the beam, the usual method of checking the tension being by plucking the threads to get the "feel" of the tension. If the warp threads were relatively slack, then the weights on the brake-arms were moved to the outer ends thereof so as to increase the braking of the section-beam, whereas if the tension in the warp had increased then the weights were moved inwardly to release the section-beam brake. The necessity for constantly changing the positions of the weights has given rise to abrupt changes in warp tension and a consequent change in the "pick point" of the web being woven.

In the manufacture of woven materials fabricated to close tolerances both as to width and pick such as ladder-tapes and slide fastener tapes, it is of primary importance that the distance from pick to pick or the distance from ladder to ladder of the tape be exceptionally uniform. Since unequal pick spacing is due primarily to non-uniform warp tension, the problem resolves itself into one of maintaining the tension in the warp substantially uniform throughout the life of the warp- or beam-section.

An object of the invention is to provide a superior warp-beam let-off which is of relatively simple construction, embodies relatively few moving parts and is capable of maintaining the tension of the warp substantially uniform for the life of the warp.

A further object of the invention is to provide a section-beam let-off mechanism with a warp-roll which is mounted on the brake-arm of the mechanism at a point such that the lift effect on the roll of the warp being pulled off of the back side of the beam is substantially proportional to the decrease in the radius at which the yarn is pulled off the section-beam.

A still further object of the invention is to provide an improved section-beam let-off wherein the lift effect of the warp on the braking-means of the beam is so closely controlled that the warp is permitted to unwind substantially continuously without jumping and under substantially-uniform tension as the goods are woven.

With the above and other objects in view, as will appear to those skilled in the art from the present disclosure, this invention includes all fea-

2

tures in the said disclosure which are novel over the prior art.

In the accompanying drawings, in which certain modes of carrying out the present invention are shown for illustrative purposes:

Fig. 1 is a broken end elevation partly in section of a section-beam let-off embodying the improved means of this invention for controlling the tension of the warp;

10 Fig. 2 is a broken plan view of the section-beam let-off on line 2—2 of Fig. 1;

Fig. 3 is a broken front elevation of the section-beam let-off of Fig. 1, but on a somewhat reduced scale; and

15 Fig. 4 is a schematic illustration of the section-beam let-off of Fig. 1 showing, by the resolution of force vectors, the ideal location of the warp-roll for effecting optimum control of the tension of the warp threads.

20 Referring to the drawings which show an exemplary embodiment of the invention, the frame of the section-beam is indicated generally at 11 and comprises a pair of parallel substantially-vertical uprights 12 secured rigidly in laterally-spaced relationship by suitable tie-beams 13 as characterizes loom structures of this type, each upright 11 being provided on its rear face 14 with an open bearing 15 adapted to rotatably support the respective pivotal-means or trunnions 16 of a section-beam indicated generally at 17.

The latter is a substantially-spool-shaped member comprising an axial cylindrical drum 18 of relatively-small diameter having disk-shaped heads 19 of relatively-large diameter at opposite ends thereof from which project the respective trunnions 16. Formed integrally or otherwise secured on the outer face of each head 19 and concentric therewith is a brake-disk 20 having a peripheral groove to accommodate a brake-band 21. A plurality of warp threads *w* is wound on the drum 18, a full beam being one wherein the spool of warp threads known generally as a warp or warp-beam is substantially equal in diameter to the diameter of the heads 19.

45 Each brake-band encircles a major portion of its respective brake-disk and is held thereon by fastening-members comprising pins 22 and 23 respectively which pivotally secure the opposite ends of each brake-band to the head 24 of a 50 brake-arm 25. More particularly, the forward end or head 24 of each brake-arm is provided with a vertical slot 26 as shown in Fig. 2 to receive the opposite ends of its respective brake-band; and transverse axially-aligned apertures 55 27 which intersect the median line 28 of the

brake-arm forwardly of its pivotal fastening-members 22 and 23, the latter being located in vertically-spaced relationship above and below the median line. The two brake-levers are supported on the frame 11 by a pivotal-member comprising a rod 29 which extends across the frame beneath the section-beam 17, the rod 29 being supported at its opposite ends in transverse axially-aligned apertures of a pair of supporting-blocks 30 which are bolted or otherwise fastened to the front faces of the respective uprights 12. As shown most clearly in Fig. 2 each brake-arm is pivotally supported on a corresponding end of the rod 29 in juxtaposition to the inner faces of the respective uprights 12 and the supporting-blocks 30 suitable washers 31 being provided to hold the brake-arms in spaced relation thereto. The ends of the rods 29 project beyond the outer faces of the respective supporting-blocks 30 and are adapted to accommodate suitable retaining-means 32 for securing the rod against endwise movement in the frame. In accordance with this construction when the brake-arms are swung down in a counterclockwise direction as seen in Fig. 1 the relationship of the fastening-members 22 and 23 of the brake-bands and the pivotal-member 29 of each brake-arm is such that each brake-band will be tightened around the periphery of its respective brake-disk so as to prevent free rotation of the section-beam 17; whereas if the brake-arms are lifted their respective brake-bands are loosened to allow the section-beam 17 to rotate more freely.

The outer free end of each brake-arm has a series of notches in its upper edge for suspending a weight 33 therefrom at various positions therealong. It will be understood that the preferred average tension at any given set of warp threads may vary from beam to beam depending upon such factors as the type of weave and the size and kind of thread being woven. Hence in order to provide for these contingencies the weights 33 are adapted to be set at various positions along the brake-arms to effect the required average warp tension on the yarn. However, having once made this setting the weight is undisturbed throughout the life of the warp-beam. Projecting forwardly from the supporting-blocks 30 of the frame 11 is a whip-roll frame indicated generally at 34 arranged to support one or more of spaced-parallel whip-rolls 35, the latter extending transversely of the beam 17 and being located in a common substantially-horizontal plane above the median lines 28 of the brake-arms.

Cooperatively associated with the brake-arms 25 is a warp-roll 36 which constitutes means for maintaining the tension in the warp substantially uniform throughout the life of the beam. To this end the warp-roll constitutes a rod 36 which extends transversely across the width of the frame and is secured at its opposite ends respectively to the respective brake-arms by suitable brackets 37 fastened thereto.

Although the theoretically exact position of the warp-roll has been discovered to be substantially at the point 360, as shown by the vector diagram of Fig. 4 and hereinafter described, for all practical purposes the warp-roll 36 may be located below the median lines 28 of the brake-arms and rearwardly of the pivotal-member 29 thereof. More particularly, assuming for the purposes of illustration only that the distance from the pivotal-member 29 of the brake-arms to the weight 33 at the outer ends thereof is substantially 16 units, then the distance, on the median lines 28

of the brake-levers, from the pivotal-member 29 to the axis of the warp-roll 36 should be substantially 5 units, the axis of the warp-roll 36 being located also substantially 1½ units below the median lines of the brake-levers. The warp threads *w* of which a plurality are being unwound simultaneously from the beam 17 are pulled off of the back side of the beam under the warp-roll 36 and then upwardly and forwardly over the whip-rolls 35 to the loom.

In the operation of the improved section-beam let-off as the warp (whether a single thread or a plurality of threads) is pulled off of the back of the beam underneath the warp-roll 36 and over the whip-rolls 35 the tension in the warp exerts a lifting effect on the warp-roll which increases as the tension in the warp increases and decreases as the tension in the warp decreases. Were it not for the improved tension controlling warp-roll of this invention the tension in the warp would vary over a relatively wide range depending upon the effective radius of the warp-beam. That is to say for a full beam the force movement acting to overcome the retarding force of the brake (assuming the latter to be substantially constant) equals the relatively-large radius of the full beam multiplied by the tension in the warp; whereas for an empty or nearly empty beam the radius of the force moment is relatively small and hence the warp must be put under greater tension in order to overcome the same braking force.

However by providing the warp-roll 36 on the brake-arms in the position shown and described herein any tendency for the tension in the warp to increase as the effective diameter of the beam decreases increases the lift effect on the brake-arms thus releasing the brake and relieving the tension in the warp as a consequence of which the warp tension remains substantially uniform or within a very limited range. In fact it has been found that with an average required warp tension of 125 lbs. the warp tension varies only from a maximum limit of 130 lbs. to a minimum limit of 118 lbs. throughout the life of the beam. In this connection reference should be made to Fig. 4 which shows a vector diagram of the forces acting on the warp-roll 36 to lift the brake-arms both when the section-beam is full and when it is substantially empty. Assuming the warp tension is substantially uniform then for a full beam the direction and magnitude of the force vectors acting on the warp-roll 36 to lift the latter are as indicated at T_w the resultant of these forces being R . Similarly for a nearly empty beam the direction and magnitude of the force vectors acting to lift the warp-roll 36 are as indicated at T_{w1} and R_1 . Resolving the resultants R and R_1 into vectors acting at right angles to a line l through the center of the warp-roll 360 and the center of the pivotal-member 29 of the brake-arms produces the vectors L and L_1 which represent the lift effect on the warp-roll. That is to say when the section-beam is full the lift effect L on the brake-arms is relatively small and hence the brake holds the beam from rotating freely whereas as the warp-beam becomes smaller in diameter the lift effect L_1 increases thereby releasing the brake and permitting the beam to rotate relatively freely so as not to over-tension the warp.

In the vector diagram of Fig. 4 the position of the warp-roll denoted at 360 is its theoretically correct position and is seen to be above the position it has in the actual application of the invention as shown in Fig. 1. Although the latter position of the warp-roll 36 is highly satisfactory

it is within the purview of the invention to locate the warp-roll in its theoretically correct position. Moreover it is reasoned that the theoretically correct position of the warp-roll for maintaining substantially uniform tension in the warp may be determined mathematically and to this end a formula has been evolved for expressing the tension in the warp in terms of the length of the brake-arms, the weight, the effective radius of the warp-beam and the lift effect of the warp on the brake-arms. It is believed that the basic formula defining the relationship of these factors is as follows:

$$T_w = \frac{\Delta_1 WE}{R + \Delta_2 EL}$$

where:

T_w =the tension in the warp in pounds.

W =the total weight hung on the end of the brake-arms.

R =the effective radius in inches at which the warp is coming off of the beam.

Δ_1 =distance in inches weight is applied from fulcrum of brake-arms.

Δ_2 =distance in inches of warp-roll from fulcrum of brake-arms.

E =the efficiency of the brake which is: inch pounds of resistance around the section-beam divided by inch pounds around the fulcrum of the brake-arms.

L =the lift factor which is the factor that multiplied by the warp tension gives the relief effect in pounds on the brake-arms at the center of the warp-roll.

This basic formula may be rearranged to give a solution for L the lift factor represented graphically in Fig. 4 in which case:

$$L = \frac{\Delta_1 WE - T_w R}{\Delta_2 T_w E}$$

By locating the warp-roll 36 in the position shown in Fig. 1 which for practical considerations varies somewhat from its theoretically correct position 360 the tension in the warp is held substantially uniform or within an extremely-small range throughout the life of the beam as a consequence of which the width of the fabric and the distance from pick to pick are maintained accurately uniform for producing woven fabrics such as slide-fastener tapes to close tolerances and for effectively eliminating the problem of ladder variation in ladder-tapes. A further advantage resulting from the maintenance of substantially uniform warp tension is the unusually smooth and even delivery of the warp yarn to the weaving point. Heretofore in most left-offs, the tension of the warp yarn builds up to a peak-point and then drops off thereby causing an intermittent braking action of the section-beam, that is to say, the latter does not unwind uniformly but unwinds in a series of short successive jerks. As a result, the warp threads have been successively pulled taut and then released, thereby creating constant variations in the width of the web being woven. By maintaining the warp tension uniform in accordance with the improved device of this invention, the braking action of the section-beam is leveled off so that the beam moves substantially continuously from pick to pick thereby providing a smooth uninterrupted flow of yarn to the web for insuring the weaving of a fabric of constant width.

The invention may be carried out in other specific ways than those herein set forth without departing from the spirit and essential charac-

teristics of the invention, and the present embodiments are, therefore, to be considered in all respects as illustrative and not restrictive, and all changes coming within the meaning and equivalency range of the appended claims are intended to be embraced therein.

I claim:

1. In a self-regulating section-beam let-off for looms: a frame; a section-beam; pivotal-means arranged to rotatably mount said section-beam on said frame; brake-means for said section-beam comprising a brake-band, a brake-arm, a pivotal-member arranged to secure the forward end of said brake-arm to said frame forwardly of the pivotal-means of said section-beam, and fastening-means arranged to secure the ends of said brake-band to said brake-arm at vertically-spaced points thereof rearwardly of said pivotal-member; a warp-roller mounted on said brake-arm at a point thereon such that the warp of said beam passing from the back side thereof under said roller forwardly to said loom lifts said brake-arm so as to reduce the braking effect of said brake-band in proportion to the decrease in effective radius of said warp-beam; and a warp-tensioning weight supported at the rear end of said brake-arm.

2. In a self-regulating section-beam let-off for looms: a frame; a section-beam; pivotal-means arranged to rotatably mount said section-beam on said frame; brake-means for said section-beam comprising a brake-band, a brake-arm and a pivotal-member arranged to secure the forward end of said brake-arm to said frame forwardly of the pivotal-means of said section-beam; a warp-roller mounted on said brake-arm rearwardly of the said pivotal-means of said section-beam the warp of said beam passing from the back side thereof under said roller forwardly to said loom; fastening-members arranged to secure the ends of said brake-band to said brake-arm at vertically-spaced points thereof intermediate said pivotal-member and said warp-roller; and a warp-tensioning weight supported at the rear end of said brake-arm.

3. In a self-regulating section-beam let-off for looms: a frame; a section-beam; pivotal-means arranged to rotatably mount said section-beam on said frame; brake-means for said section-beam comprising a pair of brake-bands, a pair of brake-arms and a pivotal-member arranged to secure the forward ends of said brake-arms to said frame forwardly of the pivotal-means of said section-beam; a warp-roller; means to secure said warp-roller to said pair of brake-arms rearwardly of the said pivotal-means of said section-beam and below the median lines of said brake-arms the warp of said beam passing from the back side thereof under said roller forwardly to said loom; fastening-members arranged to secure the ends of said brake-bands to the respective brake-arms at vertically-spaced points thereof intermediate said pivotal-member and said warp-roller; and a warp-tensioning weight supported at the rear end of each of said brake-arms.

4. In a self-regulating section-beam let-off for looms: a frame; a section-beam; pivotal-means arranged to rotatably mount said section-beam on said frame; brake-means for said section-beam comprising a pair of brake-bands, a pair of brake-arms, a pivotal-member arranged to secure the forward ends of said brake-arms to said frame forwardly of the pivotal-means of said section-beam, and fastening-members arranged to secure the ends of said brake-bands to

said brake-arms at vertically-spaced points above and below respectively the median lines thereof and rearwardly of said pivotal-member; a warp-roller; means to secure said warp-roller to said brake-arms rearwardly of the said brake-band fastening-members and below the median lines of said brake-arms the warp of said beam passing from the back side thereof under said roller forwardly to said loom; and a warp-tensioning weight supported at the rear end of each of said brake-arms.

5. In a self-regulating section-beam let-off for looms: a frame; a section-beam; pivotal-means arranged to rotatably mount said section-beam on said frame; brake-means for said section-beam comprising a pair of brake-bands, a pair of brake-arms, a pivotal-member arranged to secure the forward ends of said brake-arms to said frame forwardly of the pivotal-means of said section-beam, and fastening-members arranged to secure the ends of said brake-bands to said brake-arms at points above and below respectively the median lines thereof and rearwardly of said pivotal-member; a warp-roller;

10

means to secure said warp-roller to said brake-arms rearwardly of said brake-band fastening-members and below the median lines of said brake-arms the warp of said beam passing from the back side thereof under said roller forwardly to said loom; and a warp-tensioning weight supported at the rear end of each of said brake-arms.
